UNITED STATES PATENT OFFICE.

THOMAS FERRY, OF CLEVELAND, OHIO.

NUT-PRESS.

SPECIFICATION forming part of Letters Patent No. 737,724, dated September 1, 1903.

Application filed June 27, 1902. Serial No. 113,399. (No model.)

To all whom it may concern:

Be it known that I, THOMAS FERRY, a citizen of the United States, residing at Cleveland, in the county of Cuyahoga and State of Ohio, have invented a certain new and useful Improvement in Nut-Presses, of which the following is a full, clear, and exact description, reference being had to the accompanying drawings.

10 My invention relates to improvements in nut-presses; and it consists in the novel features of construction hereinafter described, reference being had to the drawings, which illustrate one form in which I have contemplated embodying my invention, and said invention is fully disclosed in the following description and claims.

15 The object of my invention is to provide mechanism in connection with machines of the above-named class whereby the nut is punched, cut, shaped, and trimmed by the same machine. These operations take place in succession, but by one operation of the punching mechanism.

20 Referring to the drawings, Figure 1 is a nut-press shown in elevation and embodying my invention and having parts thereof broken away to more clearly show the same. Fig. 2 is a side elevation of the same, showing the feeding mechanism and having parts broken away to show the hole punching and cutting devices. Fig. 3 is a top plan view of the bed-plate and the parts connected therewith. Fig. 4 is a top plan view of the die-plate. Fig. 5 is a section on line $x-x$ of Fig. 3. Fig. 6 is a cross-section of a stock-metal guide; and Fig. 7 is a cross-section of the trimming-die, showing the nut in elevation.

25 Referring to the parts by letters, A represents the bed-plate, from which rise suitable standards B B, in the upper ends of which the crank-shaft C is mounted. A reciprocating cross-head E is mounted in suitable ways F F on the standards B B and is connected with the crank-shaft by a connecting-rod D. A driving-pulley G is mounted upon the shaft C and has in connection therewith clutch mechanism for operating the same.

30 Secured to the bed-plate in position for feeding the metal-stock strip are the feeding device and the oiling mechanism. This mechanism is of ordinary construction. It in-

cludes the two oil-feeding rollers g g', the lower one of said rollers, g, operating in an oil-bath g², and the stock-feeding rollers f f, 55 which are driven by the ratchet-wheel f² upon the face of one, f³, of the meshing gears f³ f⁴, which are respectively secured to said feed-rollers. A suitable pawl f⁸ is mounted on a rocking arm f⁵, which is mounted axially 60 with respect to the ratchet-wheel f². This ratchet-wheel is operated by a link f⁶, pivoted to an adjustable stud f⁷, carried by said arm f⁵. An eccentric-pin c projects from the end of the shaft C, and the upper end of said link 65 f⁶ is pivoted upon the same.

The foregoing description relates to the part of the machine which is old in the art, and the following description will relate particularly to my invention and the parts thereof. 70

On the bed-plate A, between guides a a', I secure a die-plate H, provided with suitable retaining-grooves h h', the inner faces of said guides being undercut, whereby the die-blocks may be held in place with the help of wedges. 75 T-shaped guideways i i' are also provided in said die-plate for receiving tongues on the under sides of the stripper-plate J, which is substantially of the form shown in Fig. 6, having guide-pieces j j secured to its under side 80 by the screws j' j'', which pass through loose holes in said stripper-plate. The adjusting-screws j² j³ are provided for carefully adjusting these guides j j. This stripper-plate also is provided with a hole j⁵ for the punch p 85 to pass through. The dies are mounted in this die-plate H in the following manner: The punching-die M is wedged in the groove h, so that the opening in said die will register with an opening h² in said plate, the opening 90 in said plate being just slightly larger than the opening in the die, so as to permit the metal punched out to pass down through the plate freely and at the same time leave sufficient support for said die. In advance of 95 said die M is a cutting-off die N, also wedged in the groove h and so placed in relation to said punching-die M that the nuts will be cut off properly with respect to the openings previously punched therein. Beneath this cutting-off die N is the shaping-die N', which is secured in a hole in the plate h. This die has a vertical hole through which a plunger n' operates. Below the cutting-off die N in

the plate H is a runway n^3 for a plunger O, which runway is the width of a nut. The plunger O is secured on the slide O', which is so located that it will engage the lower end 5 of the plunger n', and thereby lift it, whereby the nut in the shaping-die is lifted into the runway n^3 , in which the plunger O moves.

At right angles to the line of the punching-die M and the cutting-off die N is a trimming-die P, which is of the configuration shown in Fig. 7 and is secured in a groove h' in the plate H, said die being so placed that a nut 10 will be pushed onto it by the plunger O.

Secured to the cross-head E are the respective punches—p, which is the punch to form the hole through the nut, p' for cutting off, and p², with its centering-point p³, for forcing the nut down through the trimming-die. Two guides Q Q' are movably secured upon 15 the plate H on either side of the die P, toward which they are moved by a spring Q² until both are stopped by engaging with a distance-block. These guides are provided with wings q q, each of which has a slot q³, 20 through which pass screws u, which hold the guides down and guide them. The ends of these guides are beveled outward, so that a nut may be forced between them from the shaping-die N' to the trimming-die P by the 25 plunger O. After the punch p² has forced the nut through the trimming-die P and has been raised to its upper position it leaves between the guides Q Q' a shell, which is crushed by the pressure of the spring Q² on 30 the said guide.

The slide O' is given a reciprocatory movement by a lever R, fulcrumed at r and having at one end a bifurcated portion r', adapted to operate in connection with the friction-roller 40 o', carried by said slide, and at the other end a friction-roller r². (Shown in dotted lines in Fig. 1.) This friction-roller r² is adapted to operate in a cam-groove S in a cam-wheel S', and a spring Z acts on the lever to hold 45 said roller against one face of said cam-groove. On a line with the dies M and N is an adjustable stop T, projecting to the edge of the opening of the cutting-off die N and provided with a slot t, through which passes a set- 50 screw for fastening said stop to the plate H.

The operation of the machine after it has been running for some time is as follows: As the cross-head descends a hole will be punched in the stock-strip by the punch p, a 55 nut will be cut off by the punch p' and forced down through the die N into the shaping-die N', and a nut which was over the trimming-die P will be forced down into the same to the position shown by dotted lines in Fig. 60 7, thereby trimming said nut and forcing out of said trimming-die the nut which was therein. When the cross-head goes up, the stripper-plate J prevents the punch p from lifting the punched stock-strip, the stock-feeding 65 mechanism feeds the stock-strip forward against the stop-gage T, the plunger n' lifts the shaped nut from the shaping-die, and the

plunger O moves the nut between the guides Q Q' to a position over the trimming-die, where it takes its place, resting for the time 70 being upon the nut then in said die. The next down-and-up movement of the cross-head is accompanied by a repetition of the described operations, and the shell trimmed from the nut will be crushed by the guides Q Q', which 75 are drawn toward each other when the punch is lifted from between them. As each nut comes into position over the trimming-die it pushes the trimming along toward the hole V, through which it falls. It will be understood that when the machine is first started 80 the first three or four nuts cut off will be without holes and must be thrown away.

Having described my invention, I claim—

1. In a nut-punching machine, the combination of a reciprocating cross-head carrying a plurality of punches, a cutting-off die, a shaping-die below it, a plunger movable upward through said shaping-die, a beveled slide operating said plunger and mechanism 85 for operating said slide, and means connected with said slide for moving the nut, substantially as described.

2. In a nut-punching machine, the combination of a reciprocating cross-head carrying 95 a plurality of punches, a cutting-off die, a shaping-die below it, a plunger movable upward through said shaping-die, a beveled slide operating said plunger, a plunger secured to and movable with said slide, and 100 adapted to move the nut to the trimming-die, and a trimming-die, substantially as described.

3. In a nut-punching machine, the combination of a reciprocating cross-head carrying 105 a plurality of punches, a cutting-off die, a shaping-die below it, a plunger movable upward through said shaping-die, a beveled slide operating in a suitable guideway below 110 said shaping-die for raising and lowering said plunger, and another plunger connected with said slide for moving the nut along from said shaping-die, substantially as described.

4. In a nut-punching machine, the combination of a punching-die, cutting-off and 115 shaping dies, and a trimming-die with a reciprocating cross-head, three punches secured thereto, mechanism for feeding stock metal to the punching-die and cutting-off die, a plunger for removing the nut from the shaping-die, a slide having a beveled portion for 120 operating said plunger, a second plunger secured to said slide for transferring the nut to said trimming-die, and a single shaft for operating said cross-head and said plunger, substantially as described.

5. In a nut-punching machine, the combination with the bed, of standards secured to said bed, a single shaft mounted in said standards, a cross-head operating between said standards, connections between said cross-head and said shaft, punches carried by said cross-head, a die-plate secured to said bed, a stripper-plate in connection with said die- 130

plate for stripping the metal from said punches, a punching-die, a cutting-off die, mechanism for feeding stock metal to said dies, a shaping-die below said cutting-off die, 5 a plunger for removing the nut from said die, a beveled slide for operating said plunger, a second plunger carried by said slide for transferring the nut to said trimming-die, guides for alining the nut with said trimming-die 10 and for crushing the shell, a spring controlling the movement of said guides, a cam mounted on said shaft, a lever operated by

15 said cam, said lever being adapted to operate said slide, a spring operating against said lever, and connections between said shaft and the stock-feeding mechanism, substantially as described.

In testimony whereof I herenunto affix my signature in the presence of two witnesses.

THOMAS FERRY.
